UNITED STATES PATENT OFFICE.

LEONARD MORGAN HAINES, OF STUDLEY, ENGLAND, ASSIGNOR TO WILLIAM HALL & COMPANY, LIMITED, OF STUDLEY, ENGLAND.

DESIGN FOR A NEEDLE CASE.

Application filed September 21, 1923. Serial No. 7,283. Term of patent 14 years.

To all whom it may concern:

Be it known that I, LEONARD MORGAN HAINES, a subject of the King of Great Britain, residing at Central Works, Studley, in the county of Warwick, England, have invented a new, original, and ornamental Design for Needle Case, of which the following is a specification, reference being had to the accompanying drawings, forming part thereof.

Figure 1 is a perspective view showing

the front of a needle case showing my new design.

Figure 2 is a perspective view showing the back of a needle case showing my new design.

I claim the ornamental design for a needle case, as shown.

LEONARD MORGAN HAINES.
